(57) **CLAIM**

The ornamental design for a luminaire housing, as shown and described.

DESCRIPTION

FIG. 1 is a top perspective view of a luminaire housing in accordance with the present invention;

FIG. 2 is a front elevational view of the luminaire housing of FIG. 1, the rear elevation being the same as that shown;

FIG. 3 is a bottom perspective view of the luminaire housing of FIG. 1;

FIG. 4 is a top plan view of the luminaire housing of FIG. 1;

FIG. 5 is a side elevational view of the luminaire housing of FIG. 1, the opposite side being the same as that shown; and,

FIG. 6 is a bottom plan view of the luminaire housing of FIG. 1.

The luminaire housing is shown with a symbolic break in its length. The appearance of any portion of the article between the break lines forms no part of the claimed design.

The broken lines of uniform length in FIGS. 1-3 illustrate portions of the luminaire housing of indeterminate length that form no part of the claimed design.
